(57) **CLAIM**

The ornamental design for a cutting board, as shown, and described.

DESCRIPTION

FIG. 1 is a perspective view of a cutting board;
FIG. 2 is a top plan view thereof;
FIG. 3 is a bottom plan view thereof;
FIG. 4 is a right elevation view thereof, the left elevation
view being a mirror image thereof; and,
FIG. 5 is a front view thereof, the rear view being a mirror
image thereof.
